POWER-OPERATED BUTTON POLISHER

Ronald L. L. Ganske, Porter County, Ind.

Filed Jan. 5, 1965, Ser. No. 83,276

Term of patent 14 years

(Cl. D9—2)

FIGURE 1 is a top view of this invention;
FIGURE 2 is a side elevation of my design;
FIGURE 3 is another side elevation of my design taken at 90 degrees from the view of FIGURE 2;
FIGURE 4 is a bottom view of this invention;
FIGURE 5 is a top view with the clip-on cap removed;
and

FIGURE 6 is a longitudinal section in fragment showing in detail the rotating support for a button and the removable clip-on cover.

I claim:
The ornamental design for a power-operated button polisher, as shown.
